UNITED STATES PATENT OFFICE

128,637

DESIGN FOR A LOCKET BROOCH

Seth Minasian, Cranston, R. I.

Application July 3, 1941, Serial No. 101,862

Term of patent 3½ years

To all whom it may concern:

Be it known that I, Seth Minasian, a citizen of the United States, residing at Cranston, in the county of Providence, State of Rhode Island, have invented a new, original, and ornamental Design for a Locket Brooch, of which the following is a specification, reference being had to the accompanying drawing constituting a part thereof.

Fig. 1 is a front view of the locket brooch showing my new design; and

Fig. 2 is a side view thereof.

I claim:

The ornamental design for a locket brooch, substantially as shown.

SETH MINASIAN,
